US0D1022425S

(12) **United States Design Patent** (10) Patent No.: **US D1,022,425 S**
(45) Date of Patent: ** Apr. 16, 2024

(54) **SHOE**

(71) Applicant: **adidas AG**, Herzogenaurach (DE)

(72) Inventors: **Fionn Corcoran-Tadd**, Portland, OR (US); **Chris Arias**, Portland, OR (US); **Berin Skye B**, Portland, OR (US); **Andrea Nieto Perilla**, Portland, OR (US); **Matteo Padovani**, Portland, OR (US)

(73) Assignee: **adidas AG**, Herzogenaurach (DE)

(**) Term: **15 Years**

(21) Appl. No.: **29/754,209**

(22) Filed: **Oct. 7, 2020**

(51) LOC (14) Cl. **02-04**

(52) U.S. Cl.

USPC **D2/956**; D2/947; D2/951; D2/959

(57)

CLAIM

The ornamental design for a shoe, as shown and described.

DESCRIPTION

FIG. 1 is a top perspective view of a shoe showing the claimed design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the shoe that form no part of the claimed design.

1 Claim, 7 Drawing Sheets
